UNITED STATES PATENT OFFICE.

ARTHUR CLARENCE KINZINGER, OF TORONTO, CANADA.

DESIGN FOR AN ARM-RAIL.

SPECIFICATION forming part of Design No. 32,704, dated May 22, 1900.

Application filed October 1, 1898. Serial No. 692,438. Term of patent 7 years.

To all whom it may concern:

Be it known that I, ARTHUR CLARENCE KINZINGER, a subject of Her Majesty the Queen of Great Britain, residing at the city of Toronto, in the county of York and Province of Ontario, Canada, have invented and produced a new and original Design for Arm-Rails for Vehicles, of which the following is a specification, reference being had to the accompanying drawings, forming part thereof.

Figure 1 is a side elevation of an arm-rail, showing my new design; and Fig. 2 is a cross-sectional view of the arm-rail on the line A to B.

15 My design consists of a double rail, the leading feature of which is the ornamental portion 3, which is shorter than and above the lower portion 1, as shown. The supports 2 are circular in cross-section, with the spherical 20 portion to encircle the lower portion 1 and extending therefrom and formed as shown, curving until their extremities face one another.

A series of grooves or corrugations 4 ornament the cylindrical exterior of the portion 3 and are disposed or arranged in the form of a spiral, as shown, and terminate in the supports 2. The portion 3 for symmetry of design is parallel with and follows the contour of the portion 1. The portion 1 is cylindrical in cross-section and curved longitudinally 30 and extending beyond the supports 2 and formed as shown.

Having described my invention, what I claim as new, and desire to secure by Letters Patent, is—

35 The design for an arm-rail, as herein shown and described.

In witness whereof I have hereunto set my hand in presence of two witnesses.

ARTHUR CLARENCE KINZINGER.
